LUNAR EXCURSION MODULE TOY

Robert B. Pennington, Jr., 17210 Parkland Drive,
Shaker Heights, Ohio 44122

Filed Jan. 7, 1970, Ser. No. 20,804

Term of patent 14 years

Int. Cl. D21—02

U.S. Cl. D34—15

FIG.1

FIG.2

FIG.3

FIG.4

FIG. 1 is a front perspective view of a lunar excursion module toy embodying my new design, with the side opposite to that shown being a mirror image thereof;

FIG. 2 is a perspective view of the toy module illustrated in FIG. 1 rotated over an angle of 60° in a clockwise direction from the position shown in FIG. 1, with the side opposite to that shown being a mirror image thereof;

FIG. 3 is a top plan view of the toy module when looking down on FIG. 1;

FIG. 4 is a bottom plan view of the toy module when looking upwardly from the bottom of FIG. 1.

I claim:

The ornamental design for a lunar excursion module toy, as shown and described.
